UNITED STATES PATENT OFFICE.

PAUL A. WAGNER, OF JERSEY CITY, NEW JERSEY.

PILE-CUTTING DEVICE.

Application filed March 21, 1922. Serial No. 545,399.

To all whom it may concern:

Be it known that I, PAUL A. WAGNER, a citizen of the United States, residing at Jersey City, in the county of Hudson and State 5 of New Jersey, have invented a certain new and useful Improvement in Pile-Cutting Devices, of which the following is a specification.

The invention relates to mechanism for 10 cutting the rows of loops or floats in the production of pile fabrics, and the object of the invention is to provide simple, easily operated means for severing the floats along the central lines of the rows, and in which 15 the severing operation is performed by a pinching or biting action as distinguished from the cutting or shearing action of a blade edge, whereby a long period of efficient service is assured and the necessity of 20 maintaining a keen edge by frequent sharpening or the substitution of previously sharpened blades is avoided.

The invention consists in certain novel features and details of construction and arrangement by which the above and other objects are attained, to be hereinafter described and claimed.

The accompanying drawings form a part of this specification and show an approved 30 form of the invention.

Figure 1 is a side elevation of the improved cutter, with so much of its supporting and operating means as is necessary to show its relation thereto.

Figure 2 is a corresponding vertical longitudinal section, partly in elevation, showing the cutter equipped with a pile-wire and arranged to cut the floats during the weaving operation.

Figure 3 is a corresponding plan view. The remaining figures are on a greatly exaggerated scale.

Figure 4 is a vertical section, partly in vertical longitudinal section corresponding 45 to a portion of Figure 2, showing the construction and operation of the thread-severing jaws.

Figures 5 and 6 are vertical transverse sections, taken on the lines 5-5 and 6-6 50 respectively in Figure 4.

Figures 7 and 8 are similar sections showing modified forms of jaws.

Referring to Figures 1 to 6 inclusive, 10 is the body portion of a frame or carrier, 55 preferably of sheet steel folded upon itself to form a deep open channel having the

sides brought together at the rear as at 11 and riveted to form an extension serving as a support for the body and permitting a slight degree of lateral flexibility. The extension 11 is shown as notched on the under side near the rear end to match upon a rib 12 on a fixed plate 13, and is held in engagement by a bar 14 applied upon the upper edge and clamped thereon by arms 15 extending from studs 16 on the plate 13.

When mounted to serve upon a loom, a plurality of such narrow carriers 10 and 11 will be arranged side by side on the plate 13, one for each line of floats, and when 70 mounted to serve with previously woven fabrics, a series of such carriers are arranged side by side suitably supported and adapted to be moved relatively to the goods to be treated.

At the forward end of the body portion 10 is a forwardly projecting narrow tongue 17 having its forward upper face inclined upwardly and rearwardly as at 18 and its rear upper face 19 flat and straight and enclosed between the cheeks of the body. The tongue 17 serves as a guide in engaging the row of floats, and when the device is mounted for service on a loom, may carry a pile-wire 20 as shown in Figures 2 and 3, which performs its usual function of guiding the floats to the tongue. The plane faced rear portion 19 of the tongue serves as the fixed lower jaw of the severing mechanism and is preferably of steel, spring hardened.

The upper jaw is marked 21 and is a thin plate of steel preferably extremely hard, arranged to be oscillated vertically between the cheeks of the body on a pivot 22 extending through the body at the rear. The lower margins of the movable jaw 21 at the front are beveled in opposite directions to produce a biting edge 23 so shaped as to lie parallel with and upon the plane upper face of the relatively fixed jaw 19 when the upper jaw is forced downwardly.

The movements of the upper jaw may be effected by various means; as shown, it is urged normally upward by the force of a spring 24 set in its plate near the pivot 22 and acting against the interior lower face of the body, and is forced downwardly by depressing the heel 25 of a lever 26 fulcrumed between the cheeks on a pivot 27 set in the upper portion of the body 10 near the front. The heel 25 is slightly rounded at its point of contact with the movable jaw,

and the remainder of its under face is plane to match the upper face of the jaw so that the action of the movable jaw against the lever, due to the force of the spring 24 after 5 a depression of the heel 25, is to raise the lever with the upper jaw until the plane faces of both are in contact and further movement is arrested.

Extending from the lever is an arm 36 10 preferably of spring wire, through which the lever is depressed by any suitable means, shown in Figure 1 as a pair of oppositely disposed rollers 28 supported in radial arms 29 on a revolving shaft 30, located to strike 15 the upturned end 37 of the arm 36 and by acting cam-wise thereon force the arm downward. The elasticity of the arm 36 permits the roller to pass without damage when the jaws are thus brought together while insuring 20 the desired strong bite, and the difference in length of the lever arm represented by the long distance between the pivot 22 and the point of contact of the roller 28 with the arm 36, and that represented by the 25 short distance between the pivot and the heel 25 is sufficient to bring the jaws together with all the force required to bite through any float threads presented upon the lower jaw.

30 In operation, the rollers 28 and spring 24 induce rapid opening and closing movements of the jaws which thus sever the float threads by such biting or pinching action. The threads may be fed slowly to 35 the jaws as will be the condition when the device is used in conjunction with a loom, as indicated in Figure 2, or rapidly as will be the condition when the cutter is moved along the line of floats on previously manufactured goods.

40 It has been found that a sharp cutting edge is not necessary and that the shape of such edge is not essential; the angle of 60° as shown in the drawings performs satisfactorily but may be varied.

In order to avoid unnecessary wear on the biting edge it is preferable to make the upper jaw, as shown greatly enlarged in Figures 4, 5 and 6, in which a plane rear 50 portion 31 of the lower face of the movable jaw 21, projecting almost imperceptibly below the edge 23, is arranged to contact with the plane upper face of the lower jaw 19 in the closing movement and thus arrest the closing movement after the threads have 55 been bitten through but before the edge 23 comes in actual or complete contact with the lower jaw. It is found that such construction preserves the edge without in any way lessening the biting action of the jaws.

60 In Figure 7 the fixed lower jaw is provided with a biting edge 32 and the movable upper jaw 33 is plane, and in Figure 8 both jaws 34 and 35 are edged. In both forms 65 the offset construction above described may

be employed to prevent damaging contact of the biting edges, or such construction may be omitted in all the forms shown.

I claim:—

1. In a device of the character set forth, 70 a pair of jaws one movable relatively to the other, having their adjacent faces arranged to strike in biting contact one upon the other to sever a thread presented between said jaws, and means for opening and closing said jaws. 75

2. In a device of the character set forth, 80 a pair of jaws one movable relatively to the other, having their adjacent faces arranged to strike in biting contact one upon the other to sever a thread presented between said jaws, a tongue adapted to engage a line of floats and present the threads thereof between said jaws, and means for opening and closing said jaws. 85

3. In a device of the character set forth, 90 a carrier, a fixed jaw mounted therein having a face, a tongue extending from said fixed jaw arranged to present pile threads upon said fixed jaw, a movable jaw pivotally mounted in said carrier and having a face arranged to strike in biting contact upon the adjacent face of said fixed jaw and sever such threads, and means for moving said movable jaw relatively to said fixed 95 jaw.

4. In a device of the character set forth, 100 a carrier, a fixed jaw mounted therein having a face, a tongue extending from said fixed jaw arranged to present pile threads upon said fixed jaw, a movable jaw pivotally mounted in said carrier and having a face arranged to strike in biting contact upon the adjacent face of said fixed jaw and sever such threads, and resilient means for moving said movable jaw relatively to said fixed jaw. 105

5. In a device of the character set forth, 110 a carrier, a fixed jaw mounted therein having a face, a tongue extending from said fixed jaw arranged to present pile threads upon said fixed jaw, a movable jaw pivotally mounted in said carrier and having a face arranged to strike in biting contact upon the adjacent face of said fixed jaw and sever such threads, resilient means for opening said jaws, and resilient means for closing them. 115

6. In a device of the character set forth, 120 a carrier, a fixed jaw mounted therein, a movable jaw pivotally mounted in said carrier and having a face arranged to strike upon the adjacent face of said fixed jaw, a lever pivotally mounted in said carrier and adapted to close said movable jaw upon said fixed jaw. 125

7. In a device of the character set forth, 130 a carrier, a fixed jaw mounted therein, a movable jaw pivotally mounted in said carrier and having a face arranged to strike

upon the adjacent face of said fixed jaw, a lever pivotally mounted in said carrier and adapted to close said movable jaw upon said fixed jaw, and means for yieldingly depressing said lever.

8. In a device of the character set forth, a carrier, a fixed jaw mounted therein, a movable jaw pivotally mounted in said carrier and having a face arranged to strike upon the adjacent face of said fixed jaw, a lever pivotally mounted in said carrier and adapted to close said movable jaw upon said fixed jaw, means for yieldingly depressing said lever and movable jaw, and yielding means acting upon said movable jaw for raising the latter and said lever.

9. In a device of the character set forth, a carrier, a fixed jaw mounted therein, a movable jaw pivotally mounted in said carrier and having a face arranged to strike upon the adjacent face of said fixed jaw, a lever pivotally mounted in said carrier and adapted to close said movable jaw upon said fixed jaw, a yielding arm on said lever, and means acting upon said arm for depressing said lever and movable jaw.

10. In a device of the character set forth, a carrier, a fixed jaw mounted therein, a movable jaw pivotally mounted in said carrier and having a face arranged to strike upon the adjacent face of said fixed jaw, a lever pivotally mounted in said carrier and adapted to close said movable jaw upon said fixed jaw, a yielding arm on said lever, means acting upon said arm for depressing said lever and movable jaw, and yielding means acting upon said movable jaw for raising the latter and said lever.

11. In a device of the character set forth, a pair of jaws one movable relatively to the other and having their adjacent faces arranged to open and close upon each other, a biting edge on one of said faces adapted

to co-act with the other face and sever a thread presented between said jaws, and means for preventing complete contact of such biting edge with such other face.

12. In a device of the character set forth, a pair of jaws one movable relatively to the other having a portion of their adjacent faces arranged to contact with each other in the closing movement of said jaws, and a biting edge on one of said faces adapted to co-act with the other face and sever a thread presented between said jaws, and held out of complete contact with such other face by said contacting portions of said faces.

13. In a device of the character set forth, a carrier, a fixed jaw mounted therein and having a plane upper face, a movable jaw pivotally mounted in said carrier and having a portion of its lower face plane and arranged to contact with such upper face in the closing movement of said jaws, and a biting edge forming a portion of such lower face, adapted to co-act with such upper face and sever a thread presented between said jaws, said biting edge held out of complete contact with such upper face by the contact of said plane portion of such lower face with such plane upper face.

14. In a device of the character set forth, a carrier, a fixed jaw thereon, a movable jaw loosely mounted on said carrier, the adjacent faces of said jaws arranged to strike one upon the other in the closing movement, and movable means on said carrier separate from said movable jaw and arranged to act upon said movable jaw and close the latter in such biting contact upon said fixed jaw.

In testimony that I claim the invention above set forth I affix my signature.

PAUL A. WAGNER.
